UNITED STATES PATENT OFFICE.

ALBERT W. FOIX AND AIME LEBOUVIER, OF LOS ANGELES, CALIFORNIA.

COMBINED TIE-PLATE AND RAIL-FASTENER.

1,009,496.

Specification of Letters Patent. Patented Nov. 21, 1911.

Application filed March 11, 1911. Serial No. 613,693.

To all whom it may concern:

Be it known that we, ALBERT W. FOIX, a citizen of the United States, and AIME LEBOUVIER, a citizen of France, residing at 5 Los Angeles, in the county of Los Angeles and State of California, have invented new and useful Improvements in Combined Tie-Plates and Rail-Fasteners, of which the following is a specification.

10 This invention relates to improvements in railway fasteners or tie plates, and it relates particularly to tie plates or chairs which are adapted to be secured to the ties of a road bed in such a manner as to secure 15 the flanges of railway rails thereto.

It is an object of the invention, among other things to provide a railway rail fastener or chair which is provided with an adjustable securing portion adapted to accommodate itself to different widths of rails and to be set closely against the flanges of the rails no matter what their width may be.

In the accompanying drawing forming a part of this specification Figure 1 is a perspective view of the improved rail securing tie plate, a portion of the rail being shown as seated therein and a portion of the support of the supporting tie being illustrated below the plate. Fig. 2 is a transverse sectional view through the tie plate or rail fastener.

The features of the invention will now be more fully described in detail reference being had to the accompanying drawing, in 35 which—

1 indicates a base or chair plate, 2 an overhanging rail engaging flange formed integral therewith. The base plate 1 is made of ample width to offer a firm support to a railway rail and near one edge is provided with spike receiving apertures 3, while near the other edge, the said base plate is formed with elongated spike receiving apertures 4, the said apertures being 40 elongated transversely with respect to said plate. The plate 1 is also provided upon one of its edges with a curved recess as 5 extending longitudinally of the plate and being concave in shape. Fitting in this 45 concave recess or depression 5 is an adjustable securing plate 6 having its under surface provided with a convex curvature as at 7

extending longitudinally of the securing plate. The said plate 6 is also formed with spike receiving apertures 8 which register 55 with the elongated apertures 4. An overhanging rail engaging flange 9 is formed upon the inner edge of the said plate 6. The curved seating of the said plate 6 permits of the same being rocked in the concaved recess or depression 5 to be made to fit closely the flange of the railroad rail as 10.

It will be observed that when the rail is narrow the plate 6 can be rocked inwardly 65 until its inner abutting edge 11 rests against the flange of the rail 10 and the elongated aperture 4 permits of the spikes for securing the rail 6, being driven so as to hold the said plate 6 tightly against the edge of the 70 rail flange. With a wider rail, the plate 6 cannot be rocked inwardly so far but will accommodate itself perfectly to the dimensions of the said rail.

In employing the rail fastener or chair 75 the rail is inserted beneath the fixed flange 2 upon one side, and allowed to rest flatly upon the upper surface of the said base plate 1. The adjustable securing plate upon the other side is then put in place and 80 pushed snugly forward against the edge of the rail flange after which the spikes are driven therein to hold the parts in place. The operation is substantially the same in using either form of the device illustrated. 85

What we claim is—

A railway securing device for rails comprising a chair plate having a rail engaging flange formed thereon, one edge of said plate being provided with a curved depression, and having elongated spike apertures 90 formed therein, and a flange engaging securing plate provided with spike apertures and having a curved under surface adapted to adjustably fit upon the curved depression 95 of the chair plate.

In witness that we claim the foregoing we have hereunto subscribed our names this 6th day of March, 1911.

A. W. FOIX.
A. LEBOUVIER.
